W. Buchanan, Jr.

HORSE POWER.

No 83,919.

Patented Nov 10, 1868.

WALTER BUCHANAN, JR., OF MAIN PRAIRIE, CALIFORNIA.

Letters Patent No. 83,919, dated November 10, 1868.

IMPROVEMENT IN FASTENING HORSE-POWERS TO THE GROUND.

The Schedule referred to in these Letters Patent and making part of the same.

To all whom it may concern:

Be it known that I, WALTER BUCHANAN, Jr., of Main Prairie, county of Solano, State of California, have invented an Improved Device for Confining Horse-Power to the Ground; and I do hereby declare the following description and accompanying drawings are sufficient to enable any person skilled in the art or science to which it most nearly appertains, to make and use my said invention or improvement without further invention or experiment.

The object of my invention is to provide an improved method of confining horse-powers, used more especially in connection with separators, and which, upon being moved from place to place, must be firmly fastened down by stakes or otherwise. These stakes are usually driven in the ground, upon each side of the frame, and are liable to work loose, from the motion of the machinery, or by reason of the cracks or fissures in the ground, caused by the long dry seasons of California, and which often makes it difficult to find a place to set up the apparatus, reference being had to the accompanying drawings, and letters of reference marked thereon, forming a part of this specification.

Figure 1 is a plan of my apparatus;

Figure 2 is a side sectional elevation;

Figure 3 is a front-end view; and

Figure 4 is a back-end view.

Similar letters of reference in each of the figures indicate like parts.

A is the frame of a horse-power, such as is used for a separator. The tumbling-rod passes through the cross-beam B, and communicates motion to the machine. In order to fasten this end of the frame down, a strap of iron, C, is firmly attached to the bottom of it, the ends of which are turned up, forming hooks, as shown at *a a*, fig. 3. This strap is used in order to place the attachment so low as not to interfere with the tumbling-rod.

The timbers D D extend to a sufficient distance upon each side of the machine to insure steadiness, and have, upon the under-side, straps of iron, b b, so

bent as to hook into *a a* of the strap C. Wedges, c c, are then driven into the spaces between the frame and the ends of D D, thus pressing the ends *d d* firmly down upon the ground. Light pins or stakes, e e, are then inserted and driven, if required. A box, E, is then extended across the frame, and has the links g g passing up through it from the timbers D D. These links are secured by keys F F.

At the opposite end, the bottom of the frame A is cut away, so as to rest upon the timber G, which also extends to some distance on each side, and has holes through it, into which the pins h h are driven.

From the centre of the beam G, a link, m, rises, passing through the cross-bar H, and firmly secured to it by the key n.

Straps or staples, o o o o, are fastened to the ends of the frame A, and straps P P to the beam G, through which the slides R pass, thus holding the whole securely.

By this arrangement, first, much greater steadiness is attained, for the timbers being firmly secured to the frame, and extending to some distance each side, gives it a broader base; second, it can be set up much quicker than in the ordinary manner, thus saving much time, and if pins are used at all, they can easily be placed so as to avoid cracks in the earth, while the machine need not be stopped to drive new stakes when those which have been used become loose.

Having thus described my invention,

What I claim as new, and desire to secure by Letters Patent, is—

The straps C and b b, and the beams D D and G, together with the links g g and m, with their keys, the whole constructed and operating substantially as and for the purpose herein described.

In witness whereof, I have hereunto set my hand and seal.

WALTER BUCHANAN, JR. [L. s.]
